FOLDING CHAIR

John W. Beiger, Ludington, Mich., assignor to
Carrom Company, Ludington, Mich.

Application November 18, 1931, Serial No. 575,853

4 Claims. (Cl. 155—141)

The main object of my invention is to provide a folding or collapsible chair that is simple in construction, economical to manufacture, efficient in operation, attractive in appearance, and comfortable.

Objects relating to details and economies will appear from the description to follow. A preferred embodiment of my invention is illustrated in the accompanying drawings, in which:

Fig. 1 is a perspective view of a folding chair embodying my invention.

Fig. 2 is a side elevation of the chair in folded or collapsed position.

Fig. 3 is a vertical section taken on line 3—3 of Fig. 4 with the chair in its normal or open position.

Fig. 4 is a front elevation of the chair in collapsed or closed position.

Fig. 5 is an enlarged fragmentary transverse, broken section taken on a line corresponding to line 5—5 of Figs. 1 and 3.

Fig. 6 is an enlarged detail section of the latch and keeper taken on a line corresponding to line 6—6 of Fig. 4, and

Fig. 7 is a bottom perspective view of the cushion frame and seat cover assembly.

The parts will be identified by their numerals of reference.

1 in general indicates a folding or collapsible chair embodying my invention, which comprises a pair of spaced uprights 2 constituting the back supports 3 and rear legs 4 of the chair. Outwardly curved vertically spaced cross slats 5 are secured to and between the back supports 3 and constitute therewith the rigid back 6 of the chair. 7 is the rear cross brace disposed between and near the bottom of the rear legs 4. The ends of this cross brace 7 are rigidly secured within mortises provided therefor in the inner walls of the rear legs 4. 5 are the back cross slats similarly secured to the back supports 3 so that a substantially rigid back and rear leg structure is provided.

The front legs 8 of the chair are secured together in spaced relation by the front cross brace 9 which is disposed in a horizontal plane spaced above the horizontal plane of the rear cross brace 7 for the accommodation of the lower frame 10 which is pivoted to the rear legs 4 above the rear brace 7 and to the front legs 8 below the front brace 9. The frame 10 comprises front and rear cross members 11 and 12 which are separated from each other by the side braces 13, the ends of which are rigidly secured to the inner faces of the members 11 and 12. As illus-

trated by Fig. 5, the front member 12 is provided with an integral end pivot 14 which is pivotally disposed within the socket 15 provided therefor within the front leg 8. A washer 16 separates the shoulder 17 of member 12 from the inner wall of leg 8 as shown, so that member 12 is free to rotate relative to leg 8. Both ends of member 11 are pivoted to the front legs 8, as illustrated by Fig. 5. The ends of rear member 12 are similarly pivoted to the rear legs 4.

Fig. 5 also illustrates how the cross braces 7 and 9 are secured to the front and rear legs. As illustrated, the front brace 9 is provided with tenon 18 which is disposed within and secured to the mortise 19 provided therefor in the leg 8. This construction does not mar the external finish of the legs.

The seat 20 is supported by and pivotally connected to the front and rear legs by means of the corner brackets 21 which, as illustrated by Fig. 5, are provided with upturned flanges 22 having horizontal pivot holes 23 therein for accommodating the screws 24 which are carried by the legs. As illustrated by Fig. 5, the flange 22 is separated from the inner wall of the front leg 8 by washer 25. The brackets 21 are secured to the bottom of the four corners of the seat frame 26 by means of screws 27. The frame 26 is provided with recesses 28 in the side walls thereof for accommodating flanges 22 and the heads of screws 24.

The seat frame 26 consists of front and back members 29 and 30 which are secured together by side members 31, the ends of which are dovetailed to the inner walls of the front and back members 29 and 30. The corner brackets 21, as illustrated by Fig. 4, are preferably of angular or L-shape so as to constitute joint securing means for the back and side members constituting the seat frame. This construction greatly increases the strength, not only of the seat, but also of the whole chair.

Secured to the side members 31, near the front and within the side walls thereof, are a pair of plate-like way members 32 having forwardly and upwardly inclined slots 33 terminating in downwardly extending keeper portions 34, as illustrated by Fig. 6. The plate 32 is secured to the inner wall of the side member 31 by wood screws 35.

A combined brace and latch 36 is provided under the chair coacting with the plate 32, which comprises a rear cross member 37 pivoted to sockets in the rear legs 4, as described above in connection with Fig. 5, a panel 38 secured

to slots in the cross member 37 by screws 39, and a cross rod 40 secured to the front of the panel 36 by channel-shaped brackets 41. The channel-shaped brackets 41 engage the sides of the panel 36 and are secured thereto by rivets 42, the brackets having portions which extend over the forward edge of the panel 38 provided with alined holes in the webs thereof for carrying the rod 40. The rod 40 is provided with integral lugs 40' upstruck therefrom and engaging the insides of the webs for preventing longitudinal movement of the rod relative to the panel 38. The outer ends 43 of the rod 40 extend into the slots 33 of the way members 32, as illustrated by Fig. 6. In this figure, the ends of the rod 40 are shown engaged in the keeper portion 34 of slot 33 to hold or lock the chair in its open position, as illustrated by Figs. 1 and 3.

20 For collapsing the chair, the forward end of brace 36 is elevated so as to lift the ends 43 of rod 40 out of the keeper portion 34 of slot 33. In this position of the rod 40, the seat may be swung upwardly to the position indicated by Fig. 2, the ends of the rod freely sliding in the inclined slot 33 to the end thereof. In opening the chair from its collapsed position as shown by Fig. 2, the forward portion of the seat is lowered, assisted by gravity, until approximately 25 horizontal, whereupon the ends of rod 40 are guided by slot 33 into their keeper portions 34. With the ends of the rods in the keeper portions 34 of the slot, the chair is securely locked and braced against collapsing. The weight of brace 36 tends to hold the ends of rod 40 in the keeper portions of the slots.

The seat frame 26 is provided with a rectangular groove 44 in the top thereof for receiving the rectangular cushion frame 45 which is illustrated in detail by Figs. 5 and 7. A fabric support 46 or crossed strips of burlap is secured to the top of the seat frame 26 by tacks 47, the fabric extending over the opening in the frame 26. The cushion frame 45 carries the seat cover 48 which extends over the top of the frame and around the side walls thereof. The edge of the cover 48 is secured to the bottom side of the frame 45 by tacks 49. A layer of resilient material 50, such as cotton or wool batting, is disposed between the fabric support 46 and the cover 48 and is held in place with the cushion frame 45 by a fabric sheet 51 positioned thereunder. The cushion frame 45 is removably secured to the seat frame 46 within the groove 44 by means of spaced wood screws 51, the heads of which are accessible from the bottom of the seat frame 26, as illustrated by Fig. 4.

The seat described above is claimed in my co-pending application.

60 The chair described above, constructed in accordance with my invention, is strong and rugged, but very attractive in appearance. A particularly desirable feature is the manner of securing the members together, whereby no securing members such as screw heads are visible from the outside of the chair when in use. The rigid back and rear legs prevent the chair from collapsing while being occupied, in case the latch 36 is inadvertently elevated so as to 65 release the ends of rod 40 from the keeper portions 34 of slot 33.

It is clear that various changes and modifications may be made in the details of construction and design of the above specifically described embodiments of my invention without

departing from the spirit thereof, such changes and modifications being restricted only by the scope of the following claims.

Having thus described my invention, what I claim as new and desire to secure by Letters Patent is:

1. In a folding chair of the class described having a pair of spaced uprights constituting the back supports and rear legs of the chair and having a pair of front legs and having brace means pivoted between said back legs and between said front legs, the combination of spaced apart slotted way plates depending from said seat, each having an elongated forwardly and upwardly inclined slot terminating in a short downwardly inclined keeper portion adjacent the forward edge of said seat, and a combined brace and latch panel having its forward edge substantially as wide as said chair seat and pivoted between said rear legs intermediate their bottom and the seat, and of a length to reach substantially to the front edge of the seat when the chair is unfolded, and means carried by the forward end of said panel having projecting portions slidably engaging said slots, whereby when the chair is open said projecting portions are held by gravity in the keeper portions of said way plates to prevent collapsing of the chair and in a position near the front edge of the seat to be lifted from the front of the chair and disengaged from the keeper by grasping said seat and the front of said panel and the chair collapsed by raising the front of the seat.

2. In a folding chair of the class described having a pair of spaced uprights constituting the back supports and rear legs of the chair and having a pair of front legs and having brace means pivoted between said back legs and between said front legs, the combination of spaced apart slotted way plates depending from said seat, each having an elongated forwardly and upwardly inclined slot terminating in a short downwardly inclined keeper portion adjacent the forward edge of said seat, and a combined brace and latch of a length to reach substantially to the front edge of the seat when the chair is unfolded, pivoted between said rear legs intermediate their bottom and the seat, and a cross rod substantially as long as the width of said chair seat and extending between said plates and carried by the forward end of said brace and latch and having its ends slidably engaging said slots, whereby when the chair is open the rod ends are held by gravity in the keeper portions of said way plates to prevent collapsing of the chair and in a position near the front edge of the seat to be lifted from the front of the chair and disengaged from the keeper by grasping said seat and said brace and latch and the chair collapsed by raising the front of the seat.

3. In a folding chair of the class described having a plurality of pairs of legs and a seat pivoted between the legs of each pair, the combination of means for pivotally connecting said seat to each of said legs comprising a corner bracket affixed to the bottom of said seat and having an upwardly extending flange of a width not greater than the thickness of the seat, a countersunk portion in the edge of said seat and into which said flange extends and lies substantially flush with said edge, and pivot means hav-

ing its headed end in the countersunk portion and extending through said flange and into an adjacent leg whereby said pivot means is concealed.

5 4. In a folding chair of the class described having a pair of spaced uprights constituting the back supports and rear legs of the chair and having a pair of front legs and having brace means pivoted between said back legs and between said front legs and having a seat pivoted between said back legs and said front legs, the combination of spaced apart slotted way plates depending from said seat having an elongated forwardly and upwardly inclined slot terminating in a downwardly inclined keeper portion adjacent the forward edge of said seat and a combined brace and latch comprising a wood panel of a length to reach substantially to the front

edge of the seat when the chair is unfolded and having its forward edge substantially as wide as said chair seat, said panel being pivoted between said rear legs intermediate their bottoms and the seat, and a rod carried by and lying along the forward edge of said panel and having projecting portions slidably engaging said slots, whereby when the chair is open said projecting portions are held by gravity in the keeper portions of said way plates to prevent collapsing of the chair and in a position near the front edge of the seat to be lifted from the front edge of the chair and disengaged from the keeper by grasping said seat and the front of said panel and the chair collapsed by raising the front of the seat.
